UNITED STATES PATENT OFFICE.

GEORGE T. HANCHETT, OF HACKENSACK, AND HENRY M. SHAW, OF EAST ORANGE,
NEW JERSEY.

VOLTAGE-PROTECTOR.

No. 895,854.

Specification of Letters Patent.

Patented Aug. 11, 1908.

Application filed October 3, 1906. Serial No. 337,172.

To all whom it may concern:

Be it known that we, GEORGE T. HANCHETT and HENRY M. SHAW, citizens of the United States, residing at Hackensack, Bergen county, New Jersey, and East Orange, Essex county, New Jersey, have invented certain new and useful Improvements in Voltage-Protectors, of which the following is a full, clear, and exact description.

Our invention relates to voltage protectors, or what are more commonly known to the art as lightning arresters, being devices which can be shunted around the insulation or apparatus which it is desired to protect, the voltage protector being so constructed as to be able to break down under excessive voltages and relieve the excessive pressure without damage to itself and before damage has been done to other parts of the system. The object of our invention is to produce a voltage protector which shall be simple in its construction and efficient in its operation and thus provide a new and improved device for accomplishing the results above referred to.

In all electrical distribution systems, especially those which involve aerial wiring, there are likely to be times and seasons when the electric circuits contain charges or surges of electricity at a pressure much higher than the normal pressure created by the line and often so high as to endanger the insulation of the equipment. These charges are commonly due to natural causes, principally lightning, but in the higher voltage systems, they are often due to surges caused by sudden short circuits, or open circuits, or similar disturbances.

Our invention has particular reference to a means for providing a weak spot in the insulation of the line which will break down and relieve the accumulated electrical pressure whenever the latter becomes dangerous, and which will immediately reestablish the insulation after the pressure has been reduced to the normal line value. Hitherto, in some instances, air gaps usually arranged in series with absorptive resistances have in some instances been employed in such devices. In other instances, the air gaps have been under the influence of magnetic fields or arranged to open with increased distance and automatically return as soon as the pressure is reduced. All these devices are quite complicated or uncertain. Our invention,

however, provides a means for accomplishing the desired ends, which means we have found to be more reliable and more effective, especially in the higher voltage work than devices heretofore employed.

The following is a description of our invention, reference being had to the accompanying drawings, in which

Figure 1 is a vertical section of our voltage protector. Fig. 2 is a plan view of the same.

Referring more particularly to the drawings, *c* is a jar, or container, preferably of insulating material such as glass or hard rubber. *n* is the cover therefor, which carries on its top a metallic nut *k*, in which is a threaded metallic rod *j*, which can be revolved by the milled head *m*, so as to be moved up and down. The amount of its motion can be noted by means of the disk *d* and the scale *e*. The divisions on the scale *e* record the single turns of the thread of the rod *j*, and the divisions on the disk *d* the fractions thereof.

h is a conductor leading to the circuit to be protected.

a is a bell-shaped terminal or electrode carried by the rod *j* and *b* is a tubular terminal or electrode so arranged in this particular embodiment that it can enter within but cannot touch the bell *a*.

f is an inlet pipe by means of which a stream of oil can be forced by any suitable means, such as a pump *p*, through the tubular terminal *b* into the apparatus.

g is an overflow permitting the escape or return of the surplus oil.

i is a conductor leading to the ground or any other portion of the circuit through which it is desired to equalize the surges of electrical pressure.

The action of the apparatus is as follows: The conductors *h* and *i* are connected between points which cause the apparatus to be a shunt or alternative path around the insulation it is desired to protect. Suitable means are provided for continuously forcing a stream of oil through the inlet *f* and against the inside of the bell *a*, as shown by the arrows, the return flow being provided by the pipe *g*, and the continuous circulation of oil being kept up. The milled head *m* is turned until the spark gap *x* has such dimensions that it breaks down at a predetermined potential, so that should the potential to which the conductors *h* and *i* are connected

exceed this value, the spark gap x will break down and reduce the pressure. As soon as the pressure is reduced, an arc which occurs at x is extinguished or swept out by the continuous stream of oil. It is obvious that the arrester or potential protector can be set to break down at any value within the limits of its range by simply adjusting the thumb nut m and the scale e and the disk d can be so calibrated as to read this value directly.

While we prefer to use terminals of the form shown in the drawings and to place them within a vessel or jar such as shown, our invention is not necessarily confined to such forms, since terminals of various shapes and other forms for container may be substituted without departing from the spirit of our invention. Furthermore, it is not necessary to employ a tubular terminal of any sort, although this is the form we prefer for insuring definite and accurate action. We do not, therefore, desire to limit ourselves to the exact construction shown in the drawing, but rather to include any form which embodies the substance of our invention.

What we claim is:

1. The combination of two terminals presenting opposing faces to one another, one of said terminals having a passage therethrough, and means for forcing a non-conducting liquid toward the other terminal and through said passage.

2. The combination of a container adapted to contain a non-conducting liquid, two relatively stationary terminals having opposing faces within said container and sub-

merged in said non-conducting liquid, one of said terminals having a passage therethrough, and means for causing said non-conducting liquid to flow toward the other of said terminals and through said passage.

3. The combination of a container adapted to contain a non-conducting liquid, two relatively stationary terminals having opposing faces submerged in said non-conducting liquid, the face of one of said terminals having a cavity therein and the other terminal having a passage therethrough, and means for causing the non-conducting liquid to move toward said cavity and through said passage.

4. In a voltage protector, the combination of a container adapted to contain oil, two electrodes submerged within said oil, one of said electrodes having a recess in its face and the other of said electrodes being tubular in form, and means for causing a flow of oil through said tubular electrode and against the recessed face of said other electrode.

5. In a voltage protector, the combination of a containing vessel adapted to contain oil, a bell-shaped terminal a , a tubular terminal b , a source of oil supply and a source of oil overflow, and means for causing said oil to flow through said tubular terminal.
